UNITED STATES PATENT OFFICE

2,531,271

LAMINATED TACKING STRIP AND FRAME

Vincent H. Hoehn, South Bend, Ind., assignor to
 Mishawaka Rubber and Woolen Manufacturing
 Company, Mishawaka, Ind., a corporation of
 Indiana.

Application October 17, 1946, Serial No. 703,797

2 Claims. (Cl. 155—180)

1

My invention relates to a laminated tacking strip and frame for seating structures or the like and has reference more particularly to tacking strip facilities adaptable for use with frames of the character employed in the seat bottom of M. M. Cunningham Patent No. 2,371,954 granted March 20, 1945.

With such frames, or frames of a similar character, it is oftentimes desirable to fasten upholstery material or the like to the frame but the frame being of metal and space limitations such that ordinary tacking facilities cannot be employed, no satisfactory way has been available heretofore for fastening upholstering material to such frames.

I have found, however, that the difficulty may be overcome by employing a thin strip of fibre board or other material capable of holding a tack, and securing this strip against the side of the frame so that when a tack is driven into the strip it clinches against the metal frame and thereby insures a fastening of the tack which will hold it securely in place.

The principal objects of my invention are, to provide improved facilities for securing upholstery material to a metal frame; to employ tacking facilities which do not add materially to the thickness of the frame; to avoid any appreciable effect on the flexibility of springy frames; and to insure a secure and dependable tacking of materials to the frame, these and other objects being accomplished as pointed out more fully hereinafter and as shown in the drawing in which:

Fig. 1 is a vertical sectional view of a seat cushion assembly employing a metal frame to which upholstery material is attached in accordance with this invention;

Fig. 2 is a bottom view of a fragmentary portion of the seat bottom of the Fig. 1 structure, with parts broken away to disclose details of construction, and

Fig. 3 is an enlarged fragmentary section through the bottom edge of the structure of Fig. 1.

Referring now to the drawing, the reference number 5 indicates a cushion body which is illustrated as composed of spongy rubber or the like with openings 6 extending upwardly from the bottom nearly to the top thereof, and 7 indicates, as a whole, a bottom or base on which the cushion body 5 is mounted.

This bottom or base 7, which is similar to that disclosed in Cunningham Patent No. 2,371,954 and may be made in accordance with Cunning-

ham Patent No. 2,314,318 of March 16, 1943, comprises two layers 8 and 9 of strong, substantially non-stretchy fabric, such as duck or canvas, which are adhesively joined together and secured in tightly stretched condition on a marginal frame comprising a flat, relatively wide metal strip 10 which is secured flatwise between the margins of the two fabric layers 8 and 9, preferably by double rows of stitches 11 along the inner 10 and outer edges of the metal strip 10, and extends continuously therearound. Ordinarily a metal strip 10 approximately five-eighths of an inch wide and one-eighth of an inch in thickness has been found satisfactory for this purpose.

15 The frame 10 is of substantially the same shape as the periphery of the seat or back cushion with which it is designed to be used, and usually forms a continuous ring of that shape. It may be molded in the desired shape, or it may be cut 20 from flat stock, but it is preferred to use a flat steel strip shaped to the required form and having the ends welded together to form an endless flat frame.

Oftentimes it is desirable to secure a cushion 25 covering or other upholstery material to the margin of this bottom or base by tacking but usual tacking facilities could not be employed therewith.

I have found, however, that tacking facilities 30 which may be satisfactorily incorporated in the seat bottom or base may be provided by securing a thin strip 12 of suitable material to one side of the metal ring or frame 10 and securing this composite ring and tacking strip between the 35 margins of the two fabric layers 8 and 9, the tacking strip 12 being relatively thin so that tacks driven therein clinch against the metal ring or frame and of a suitable material to hold the clinched tack securely in place.

40 The tacking strip 12 is preferably of fiber board or similar relatively strong material and is of substantially the same shape, width, and thickness as the metal frame 10, and may be riveted to the ring or frame 10 as indicated at 13 or may 45 be cemented or stapled thereto, or it may merely be assembled with the ring or frame 10 between the two layers of fabric 8 and 9 and held in position by the stitching 11 on each side of combined frame 10 and strip 12.

The two sheets or layers 8 and 9 of fabric are 50 coated on their inner faces with a suitable material to insure bonding thereof securely and permanently together, rubber compounds or compositions being preferable for the purpose. These 55 are vulcanized thereafter to insure an insep-

arable relation between the two layers and to enhance the strength of the two ply assembly. The presence of the rubber affords elasticity, and the vulcanizing results in some shrinkage which increases the tensioning of the fabric. The metal frame 10 and the tacking strip 12 which are incorporated marginally between the fabric layers 8 and 9 are thus secured therebetween, not only by the double rows of stitching 11 but also by the bonding and vulcanization together of the said layers.

With this laminated frame 10, 12 a cushion covering 14 may be applied very readily over the cushion body 5 by merely turning in the edges of the covering under the frame 10, 12, as indicated at 15, and securing these turned under edges 15 to the frame 10, 12 by tacks 16 at suitable intervals which are driven through the tacking strip 12 and clinch against the metal frame 10 as indicated at 17.

Thus, although the tacking strip 12 is quite thin and does not materially increase the thickness of the marginal frame on which the fabrics 8 and 9 are stretched, a very secure attachment of the covering 14 thereto is assured by the clinching of the inner ends of the tacks against the metal strip 10.

This base is sufficiently thin and lightweight in design so that it may be combined with a cushion to form a compact, easy to handle, seat unit, which makes it highly desirable for installation in automobiles, railroad passenger cars, buses, airplanes, and elsewhere, where lightness of weight and compactness are required.

The tacking strip 12 may, of course, be made of various materials other than fiber board. It may be of wood or plywood, or it may be made of any material which can be penetrated by upholstering tacks. I prefer to use fiber board strips because a thin strip of this material appears to be the most effective in retaining the tacks in place.

While I have shown and described my invention in a preferred form, I am aware that various modifications can be made therein without departing from the spirit of my invention, the scope of which is to be determined by the appended claims.

What is claimed is:

1. In an upholstery structure, the combination of a seat base or the like comprising a fabric panel having a marginal pocket of fabric therearound and a relatively thin flat marginal frame composed of superposed laminations respectively of metal and of a tough tack penetrative material and enclosed in said pocket and thereby holding the panel tautly outstretched, said base having another fabric secured thereto by fasteners engaged through the latter fabric and through the fabric of the pocket and through the tack penetrative lamination of the frame and clinched against the metal lamination of the frame.
2. In an upholstery structure, the combination of a seat base or the like comprising a fabric panel having a marginal pocket of fabric therearound and a relatively thin flat marginal frame composed of superposed laminations respectively of metal and of a tough tack penetrative material and enclosed in said pocket and thereby holding the panel tautly outstretched, said base having a cushion thereon and said cushion having a fabric covering thereon with marginal edges of said covering secured to the base around the margin thereof by fasteners engaged through said covering and through the fabric of the pocket and through the tack penetrative lamination of the frame and clinched against the metal lamination of the frame.

VINCENT H. HOEHN.
